CHECK PERFORATOR

James Carroll Rice, 1 Pinecroft Road,
Asheville, N.C. 28804

Continuation-in-part of abandoned design application Ser.
No. 318,880, Dec. 27, 1972. This application Dec. 11,
1974, Ser. No. 531,594

Term of patent 14 years

Int. Cl. D19—02

U.S. Cl. D64—10

FIG. 1

FIG. 3

FIG. 2

FIG. 1 is a perspective view of a check perforator showing my new design in an open condition;

FIG. 2 is a top plan view in a closed condition; and

FIG. 3 is a right side elevational view, the opposite side being a mirror image thereof.

This is a continuation-in-part of design application Ser. No. 318,880 filed Dec. 27, 1972, now abandoned.

I claim:

The ornamental design for a check perforator, substantially as shown and described.
